KILN HOOD AND SUPPORT.

Application filed May 10, 1926. Serial No. 107,858.

This invention relates generally to the brick making art and particularly to the provision of a traveling structure arranged to be moved from kiln to kiln for supporting 5 a kiln during the firing process and for carrying a hood or kiln closure to collect and carry away the vapors and hot gases.

In the brick making art the wet molded bricks are first dried, either under normal 10 atmospheric conditions or under conditions not greatly departing therefrom. Brick so dried are then built up into a kiln, a part of which is usually formed of burnt brick. Special supporting means are usually erected 15 for sustaining the kiln walls during the contraction and expansion incident to the firing process. The firing process is first conducted slowly to drive off water held in the brick and not removed by the first drying stage. This is known as the water smoking 20 stage during which the gases issuing from the kiln are heavy with water vapor. Following this stage the intense firing is carried out to bake the brick. During the 25 heating process much heat is ordinarily wasted and the combustion gases discharged from the kiln are troublesome to the workmen and also to the residents in the surrounding territory.

The present invention aims to provide a 30 structure which can be associated with a kiln to support it during the firing stage and to collect the heated gases therefrom for utilizing the heat and for discharging the gases into a high stack.

A further object of the invention is to provide a structure of the above character which is capable of being moved from kiln to kiln.

A particular object is the provision of 40 supporting means for the kiln wall to be carried by the movable structure.

Another object of the invention is the provision of flexible wedge supports for the kiln wall which automatically yield on expansion of the kiln and which will reposition 45 themselves on contraction of the kiln.

Still another object is to provide a gas collecting hood for the kiln capable of sealing the top thereof to permit drawing the 50 heated gases from the kiln for use elsewhere as in the initial drying of the brick.

A further object of the invention is to pro-

vide dampers in the hood capable of rendering the hood ineffective to collect gases from the kiln and to permit them to escape when 55 desired, as in the case during the water smoking stage.

Still another object is to provide a hood having mechanically operated means associated therewith for sealing the space between 60 the hood and kiln.

A further object is the provision of automatic duct registering and duct valve controlling mechanisms associated with the 65 hood.

Still other and ancillary objects and advantages of the invention are contemplated as will become more apparent from the ensuing description of an exemplary embodiment of the invention as disclosed in the accompanying drawings, in which

Fig. 12 is a detail view in a vertical plane of the duct registering and damper operating mechanism.

Fig. 13 is a plan view of the mechanism shown in Fig. 12 taken on the line 13—13 thereof.

The apparatus shown in the drawings is given only by way of explaining the objects, the nature, and the advantages of the invention. However, although it is the preferred embodiment of the invention, its illustrative use is not to be construed as a limitation of the invention to the precise details of construction and the arrangements of the parts disclosed and described. It is to be understood that the invention is susceptible of modifications in construction and arrangement and that it comprehends all such modified forms and departures as may fall within the scope of the appended claims.

In general the presently described embodiment of the invention comprises a traveling structure housed in a long shed. The shed shelters a series of kilns as they are being successively built up, fired, cooled and torn down. An exhaust duct runs along the length of the shed and is provided with dampered ports which are adapted to register with corresponding ports in a hood forming a part of the traveling structure. One portion of the traveling structure is supported by a gantry leg running upon a track on the ground or floor of the shed. The gantry leg carries adjustable supporting means for the adjacent wall of the kiln, the construction being such that the supports will automatically adjust themselves to the variations in the kiln dimensions which result from expansion and contraction during the firing process. The kiln hood is provided with movable sealing means adapted to close a space at the top of the kiln intervening between the hood structure and the top of the kiln walls. Suction is applied to the exhaust duct to draw heated gases into the hood and thence into the duct. The sealing means not only prevents the drawing in of cooler surrounding outside air, but also prevents the escape of the heated gases from the kiln to the shed. Controllable dampers are also provided in the hood to permit the escape of water vapor in the preliminary stages and also to admit when necessary cooler gases from the space above the hood in order to maintain the metal structure sufficiently cool to prevent damage by overheating.

Referring to the drawings, Figure 1 shows a cross section of a shed used for the brick kilns. Generally described it has a roof supported on columns 16 and 17. On the floor of the shed along one side wall thereof there is a railway track 18 to the right of which the kilns are built up. The columns 16 and 17 also support two lines of I-beams 19 near the top for track rails 20 upon which runs an overhead crane 21 used in the work on the kilns. For the purposes of the pres-

ent invention it is best to provide the crane as high in the shed as possible and preferably spanning the whole width of the shed shown or at least a greater width than the space occupied by the kiln. The crane is thus so removed in order to provide a space for the traveling structure over the kilns and beneath the crane.

In the present instance the traveling structure comprises a hood portion 22 supported at one side on a track 23 carried on the columns 17 and on the other side by a gantry leg structure 24 reaching to the ground and rolling on a track 25. Alongside the shed extends a tubular conduit 26 with which is associated an exhaust fan 26. The exhaust duct 26 is carried on bracket arms 27 extending outwardly from the posts 17. These bracket arms in the present instance also extend inwardly and carry the track 23 for the hood. A plurality of spaced ducts 28 lead from the conduit 26 toward the hood structure 22. The relation of these structural parts will be made more apparent hereinafter as the description proceeds.

Each kiln used in connection with the structure herein described is approximately 130 feet long by 35 feet wide and fifteen feet high, tapering upwardly. In view of the size of the structures herein involved, it must be understood that the drawings do not disclose all the details of construction, but only such parts as are essential to the invention and such other parts as may be conveniently shown.

The crane 21 may be used to move the traveling structure, which as a unit is slightly larger in size than a kiln to be covered thereby. In Fig. 2 the hood structure 22 is shown in plan view in outline only. For convenience in constructing the hood, in moving it from place to place, or in using it, it is preferably made in two similar sections 22^a and 22^b which can be rigidly secured together to form the desired unit hood. However, the structure of each section is such that without any alteration the two sections may be separated from each other and used independently as single hoods. Since the two sections are duplicates, but one will be described. In Fig. 3 the two sections are shown placed end to end with abutting flanges 29 and 29^b arranged to be fastened together when desired to form a large unitary hood structure.

In general, each section (Figs. 4, 6 and 7) comprises four transverse I-beams 30 across which are placed five lines of spaced I-beams 31 longitudinally of the section. Four lines of the I-beams 31 are placed on top of the transverse beams 30 and one line 31^a, at the gantry leg side, is placed below the level of the remaining longitudinal beams, being in the present instance placed between the 130

transverse beams 30 so that the tops of the perpendicular beams 30 and 31^a are flush. Gusset plates 32 are used at the joints and intersections to provide a rigid connection 5 for the hood skeleton.

On the so-called front side of the structure, the ends of the transverse I-beams 30 are supported from the ground track 25 by the gantry leg construction 24, later to be 10 described, and on the other side by a number of trucks which run on the track 23. Each transverse I-beam is connected to a truck comprising a short I-beam 33 forming a T or L-joint with each cross beam 30 15 (Figs. 4 and 5). Each truck beam 33 bears at its ends a wheel bracket 34 with a flanged wheel 35. The arrangements of the trucks on the two middle cross beams 30 are identical, but the relation is varied slightly for 20 the end beams in order to permit a duplicating construction for the two sections and to permit the desired interfitting relation. As seen in Fig. 5 the two end truck beams 33 are shorter at their outer ends as indicated 25 at 36 and 37. The inner end of the end truck beams 33 in each instance is the same in length as the ends of the middle truck beams 33. On the free end of the section the truck-beam end 36 is provided with a 30 bracket 34 and wheel 35. On the jointed end of the section the truck-beam end 37, in place of receiving a bracket 34 and wheel 35, is so formed that it abuts a similar beam end on the other section 22^b, this beam being 35 designated 37^b (Fig. 5).

The truck beams 33 are rigidly interconnected by channel bars 38, 38 and 39 spanning the space between them. The channel bar 39 at the divisional end of the section is 40 of greater size and strength than the other bars 38 in order to aid in supporting the end cross beam 30 independently of the corresponding truck portion on section 22^b.

On the front side of the structure (Fig. 3) the supporting gantry leg for the cross 45 beams 33 comprises I-columns 40 rigidly secured to the cross beams. The columns 40 rest upon a sill 41 carrying wide double flanged wheels 42 running on track 25. Diagonal cross ties 43 are provided between the 50 columns. Along the top and on the outer side of the columns a connecting channel bar 44 completes the frame structure.

The skeleton framework of the hood as 55 above described, provides a base on which to build up the desired hood form, and upon which to support various operating appurtenances used in connection with the hood and with the kiln over which the hood is 60 placed. In using the hood it is placed over an open top kiln to draw the hot gases away and to lead them to the exhaust duct 26.

In the initial stages of firing a large 65 amount of water vapor is driven off which is not useful in drying the brick and which

therefore is not taken into the duct 26. Accordingly means is provided to permit the escape of this water vapor. It is important to protect the skeleton framework from the corrosive action of the gases and also as 70

much as possible from the intense heat of the gases. For this reason the inside of the hood skeleton is lined with sheet metal to form the hood. In the spaces of the framework openings are formed in the hood and 75 are provided with dampers to permit the escape of water vapor and also to permit drawing in cooler outside air. The sheet metal lining of the hood is generally designated by the numeral 45. It is dipped downwardly as shown at 46 (Fig. 6) to pass under the cross beams 30 leaving the beams exposed at the top of the hood. All along the gantry side the sheet metal surface 45 is inclined as shown at 47 (Fig. 7) between the 80 lower line of the longitudinal beams 31^a and the adjacent higher line 31. This structure forms a sort of inverted trough between each pair of adjacent cross beams. The dampers are illustrated in the plan view in Fig. 4, 85 these being in the present instance rectangular in shape and alined in pairs between adjacent cross beams 30. Two dampers are placed within each opening of the skeleton frame. Each damper is formed by a short 90 rectangular box-like opening 48 projecting up from the sheet metal surface 45. A common shaft 49 passes through each line of dampers and carries in each box structure a butterfly member 50 (Fig. 6). The two 95 shafts 49 associated lengthwise of each trough are interconnected as by a chain 51 passing over sprocket wheels 52 (Figs. 3 and 4). One of the connected shafts has a 100 depending chain 53 passing over a sprocket wheel 54 so that each group of connected dampers may be simultaneously operated from the ground.

It is particularly desirable that the hood fit tightly over the kiln to seal it so that the 110 exhaust fan may draw through the kiln. Self-adjusting means is provided for this purpose which may be readily withdrawn from effective position to permit moving the hood structure.

Movable means are therefore employed for closing or sealing the space between the hood and the kiln walls. Because of the contraction and expansion of the kiln during the process of firing, the closing means are 115 made in independent units, each unit being adapted to yield so that the variation in various parts of the walls may be met. The sealing means preferably assumes the form of a plurality of independent flaps arranged 120 around the edge of the hood. These are represented by the numeral 55 (Figs. 4 and 6 to 8). The flaps are placed about the four edges of each section so that each section may, when required, be used independ- 125

ently as a complete hood. The flaps at the long edges of the hood are secured to the hood proper by a piano-hinge joint 56 (Figs. 8 and 11) to a vertical portion 45^a of the sheet metal which forms the body of the hood. Each flap is suspended by a chain 57 which is secured to a shaft about which it may be wound to raise the flap. In Fig. 4 there are shown four such shafts designated 10 58, 59, 60 and 61, there being one for each edge of the hood section. The shaft 58 is located along the division-line end of the section and is connected through gearing 63 (Fig. 4) to a pull chain sprocket 64 by 15 means of which the flap chains 57 are wound up to raise all the flaps 55 along the divisional edge. In Fig. 6 the flaps 55 on section 22^a and the flaps 55^b on the section 22^b are shown in vertical position, being ar- 20 ranged face to face when the two sections abut each other thereby to form a seal between the two sections. The chain winding shaft 59 on the gantry side is connected by gearing 65 (Fig. 4) to a pull chain sprocket 25 wheel 66 for similarly operating all the gantry side flaps. On the free end the chain winding shaft 60 is connected by gearing 67 to a pull chain sprocket 68. The remaining shaft 61 is similarly related to gearing 30 69 and sprocket wheel 70.

In Fig. 5 there is a space between the adjacent trucks 33 under the spanning beams 38, 38 and 39. Each space provides access 35 to an exhaust port from the corresponding inverted trough in the hood. In the present instance (Figs. 5, 12 and 13) there are three rectangular ports 71 in each hood section from which there projects a short rectangular conduit 72 extending outwardly 40 past the vertical line of track 23.

An automatic arrangement is used by 45 means of which communication is established between the hood and the exhaust duct 26 only when the ducts 28 and 72 register prop- 50 erly with each other. Spaced along the shed are the branch pipes or ducts 28 above men- 55 tioned, which lead into the main duct 26 (Fig. 11), these being spaced apart (Fig. 4) the same as the hood ports 72 and being sim- 60 ilarly shaped. The conduits 28 are dampered by butterfly valves 73 (Figs. 11 and 12), each valve being mounted on a shaft 74 which has externally of its duct a crank arm 75 (Fig. 12). One side of the valve is weighted as 65 shown at 76 so that it will close automatically. Operating means for the butterfly valve is provided so that as the hood and ducts are being positioned in proper regis- 70 tration the valve will open. The registry 75 of the ducts is accomplished by providing each of the two opposed conduits 28 and 72 with flanges (Fig. 12) adapted to abut each other. The flange 77 on the conduit 28 is fixed thereto. The flange 78 on the hood duct is carried on a sleeve 79 which slides

in and out of the duct 72. At the bottom of the duct 72 near the end thereof there is provided at each side a pivot 80 upon which a two-armed lever or bell crank is mounted. One arm 81 is pivotally connected at 82 to the sleeve flange 78 so that the sleeve and flange may be moved toward and away from the duct 28. The other arm 81^a is used for moving the bell crank and for this purpose it carries a flexible extension 83 project- 75 ing into the path of a cam 84 mounted on the operating shaft 85. The shaft 85 is preferably common to all the ducts on each section and is operated by a pull chain sprocket 86 (Fig. 4). Each cam 84 is point- 80 ed and when turned in one direction it urges the movable flange toward the fixed flange (full line position of arm 83 in Fig. 12). The resiliency of arm 83 provides a yielding 85 connection between the common operating shaft and each pair of registering ducts. It permits the cam to pass beyond the point necessary to effect closure, the flexible arm yielding to take the excess motion. This construction takes care of any irregularities 90 in adjustment and in construction and readily permits all of the ports to be closed by the same operation.

The damper-opening means for the conduit 28 is associated with the duct registry 95 mechanism for operation thereby. Arm 81 is extended and is provided at the end with a hooked portion 87 (Fig. 12) extending over the flanges. Pivoted to the framework of the shed at 88 there is a swinging arm 89 having a slotted end 90 engaging a pin 91 on the crank arm 75 of the damper. A projecting cam lug 92 on the arm 89 is positioned in the path of the hook portion 87 as the latter moves with the bell crank. The 105 arrangement is such that the swinging arm 81 moves the arm 89 causing the weighted 110 damper 73 to be turned and the duct thereby opened. It is obvious that this takes place automatically on the proper regis- 115 tration of the two duct ends. On removal of the duct 72 the weight 76 automatically 120 closes the damper.

As before mentioned, a kiln does not 115 maintain its original dimensions. There is a certain degree of expansion and contraction during the process of heating and cooling. For this reason it is customary to support the brick walls defining the kiln to ensure that they will not topple over. In 120 the present instance, the supporting means is carried by the traveling structure. Self-adjusting supports are used. In describing the nature of the supporting means, it should be pointed out that the exhaust side 125 of the hood is substantially fixed by virtue of the wheels 35 holding this end of the structure substantially rigid laterally on the track 23. As the hood itself is subjected to heating and cooling, its expansion is con- 130

siderable because of its large size. For this reason the wheels 42 on the gantry leg 24 have been made quite wide so that they may slide laterally on the track 25 to permit the expansion of the traveling structure.

As a result of this condition it is possible to arrange a substantially fixed wall-supporting means on the exhaust side of the traveling structure, and if it is desired, to 10 mount adjustable wall-supporting means on the gantry side.

Portions of the movable structure when positioned adjacent the kiln provide a substantially fixed backing support alongside 15 and spaced from a kiln wall. Into the gap or space between the kiln wall and the backing support there are positioned wall supporting means which are designed automatically to span the gap irrespective of variations of the gap due chiefly to contraction 20 and expansion of the kiln. To permit expansion, the wall supporting means are made to yield to compression, and to permit contraction, the wall supporting means are 25 adapted to yield to a release of pressure thereon.

The wall supporting means herein used are preferably laterally resilient wedges indicated by the triangular structures designated 95 in Fig. 11. Each is a strip of metal bar bent into the substantially triangular shape shown. Means is provided for spacing said wedges apart along the walls and to permit independent adjustment 30 of each wedge vertically. A rigid horizontal support 96 is hung by arms 97 from the superstructure of the hood. Each supporting triangle is mounted for sliding vertically with relation to the horizontal supporting bar 96. The slidable relation is obtained by mounting a strap 99 horizontally along the support (Fig. 11a), the strap and bar creating a vertically extending opening having a narrow space 100 in which one leg 98 of the triangle may be positioned for vertical movement, and having also a larger space 101 into which the same leg of the triangle may be moved. The space 101 is made sufficiently large so that the leg of the triangle 35 may be turned therein to move the triangle into a position parallel with the kiln. This structure permits permanent mounting of the triangular wedges and permits their being readily displaced from supporting position 40 so that the structure may be moved without the supports interfering with the kiln walls. The shape and structure of the triangle is important in that it provides a flexible wedge to be compressed between the supporting bar on one side and the brick wall 45 on the other. Excessive pressure on the triangle causes the mounted leg to flex (dotted lines, Fig. 11) thus permitting the leg adjacent the kiln to be carried outwardly in 50 yielding to expansive force. Upon contrac-

tion, however, the wedge becomes loosely mounted, and because of its slidable relation to the horizontal support 96, it drops and always maintains a fixed lateral support as the kiln contracts.

On the gantry leg similar triangular supports are employed, these being provided in two horizontal series (Figs. 3 and 8). Each series is similarly mounted. The wedge supports are the same as used on the rear side 70 and are likewise designated by the numeral 75 95. The same slip mounting is used, and the mounting parts are similarly designated (Figs. 9 and 10). On the gantry side the strips 99 are secured to a laterally movable angle bar 102 corresponding to the fixed bar 96 on the opposite side of the structure. These angle bars 102 are thus arranged in three pairs, one pair for each space between 80 columns 40. Each bar 102 is horizontally 85 slidable on brackets 103 carried on the columns 40, and the motion on said brackets is controlled by hand wheels 104 with shafts 105 threaded into the bars. This construction permits an operator not only to move 90 the triangles if necessary as the traveling structure expands but also to adjust them for the movements of the kiln.

The heat for burning the bricks is frequently supplied by the use of fuel oil burners. Since the fire is used only while the traveling structure is in place about the kiln, the oil burners and the supply pipes are preferably mounted on the traveling structure. Fig. 1 shows diagrammatically a 95 number of burners designated 106 mounted on the gantry leg 24. An oil pipe 107 and a steam or air pipe 108 leading to each oil burner are also mounted on the gantry leg. They are adapted for connection to suitable 100 outlets (not shown) as the traveling structure is moved from place to place.

When a kiln is built up and made ready for receiving the lateral supports and the hood, the structure is then moved, either in 105 sections or as a whole unit, to its position around the kiln. As the structure is being moved toward the kiln the supporting triangles are all arranged laterally as shown in Fig. 9 so that they clear the kiln walls as 110 they pass. Also the flanged sleeve 79 (Fig. 12) on each hood duct is withdrawn to its innermost position by operation of the cams 84. All the flap chain shafts 58, 59, 60 and 61 have the chains 57 wound thereon to raise 115 the sealing flaps so that in the motion of the structure the flaps will clear the top of the kiln. When the hood is positioned over the kiln the flaps are dropped so that the chains 57 become loose. Each flap then finds its 120 own location corresponding to the local level of the wall. The triangular supports are then raised and turned in their mountings so that they support the wall of the kiln as shown 125 in Figs. 8 and 11. The firing is started and 130

the dampers 51 opened to permit the escape of water vapor. Later these are closed when it is desired to draw off the heat and gases from the kiln. At this time the shaft 85 (Fig. 12) is turned to move the ducts of the hood and the exhaust into register. This automatically swings the arms 89 to open the dampers 73. Suction on the exhaust duct 26 then draws the heat and gases through the kiln into the hood and through the duct. As the heat becomes more intense it may be necessary to cool the hood and skeleton frame by admitting cooler air into the top of the hood. This may be done by opening the top dampers provided in the hood.

We claim as our invention:

1. A traveling structure adapted to be moved into place over a brick kiln comprising, in combination, a gas collecting hood, rolling supports therefor, means carried by said parts for supporting the walls of the kiln, and other means carried by said parts for closing the space between the top of the kiln and the bottom of the hood.

2. A traveling structure adapted to be moved into place over a brick kiln comprising in combination, a gas collecting hood, rolling supports therefor, means carried by said parts for supporting the walls of the kiln, other means carried by said parts for closing the space between the top of the kiln and the bottom of the hood, said hood being constructed to provide a discharge port for the gases collected, and valved ventilating means in the hood to permit the free escape of gases from the hood other than through said port.

3. A traveling structure adapted to be moved into place over a brick kiln comprising, in combination, a gas collecting hood, supports therefor, means attached to one of said parts for supporting the walls of the kiln, means on the hood adapted for connection to an exhaust duct, and means for ventilating the hood to permit the escape of gases from the hood otherwise than through said exhaust duct.

4. A traveling structure adapted to be moved into place over a brick kiln comprising, in combination, a gas collecting hood, rolling supports therefor, and means carried by said parts for supporting the walls of the kiln.

5. In a device of the character described, a hood or cover arranged to collect gases from a brick kiln for discharge into a duct, said hood having dampers therein to be open for the escape of gases unsuitable for discharge into said duct.

6. A traveling structure for use in firing brick kilns comprising, in combination, a gas collecting hood adapted to be rolled from kiln to kiln, kiln wall supports movable with the hood and adapted to support the walls

of the kiln when the hood is fixed over said kiln, means providing a port in the hood through which the collected gases may be discharged, and other means for venting the hood to permit the escape of gases otherwise than through said port.

7. A traveling structure adapted to be moved from kiln to kiln, said structure having mounted thereon a fuel burner for the kiln, and a hood to collect hot combustion gases from said burner after passing through the kiln.

8. Means for supporting the wall of a brick kiln comprising, in combination, a main supporting member adapted to be positioned adjacent the wall and providing a vertically extending opening therein having a narrow portion and a wide portion, a laterally resilient wedge-shaped member having a part thereof mounted for vertical sliding in said opening, said member being incapable of turning on a vertical axis while positioned in the narrow portion and being capable of turning on a vertical axis when positioned in the wide portion.

9. Means for supporting the wall of a brick kiln comprising, in combination, a main supporting member adapted to be positioned adjacent the wall of the kiln and providing a vertically extending opening therein, and a strip of metal bent into a substantially triangular shape with one leg mounted in said opening for vertical sliding therein.

10. An automatically adjustable supporting means for walls of brick kilns comprising, in combination, a laterally flexible wedge, and means for mounting said wedge to permit dropping of the wedge on releasing lateral pressure thereon.

11. An automatically adjustable support for the wall of a brick kiln comprising a wedge, and a backing support for holding said wedge against a wall of a kiln, said support permitting the wedge to drop on a separating movement of the support and kiln.

12. Means to support a wall of a brick kiln comprising a triangular strip of metal having flexible sides, and means for mounting one leg of the triangle at a point intermediate the ends of said leg to permit flexure of the mounted leg by pressure between the triangle and the support.

13. Means for supporting the wall of a brick kiln comprising, in combination, a substantially fixed support positioned alongside a kiln wall, an adjustably mounted member paralleling said wall and adjustably movable toward and away therefrom, and a plurality of resilient means spaced along said member for yieldingly supporting the wall.

14. A brick kiln wall-supporting means comprising, in combination, a substantially fixed support paralleling a wall of the kiln,

and a plurality of resilient means spaced along said member for yieldingly supporting the wall.

15. A brick kiln wall-supporting means comprising, in combination, a substantially fixed support paralleling a wall of the kiln, and a plurality of independent vertically adjustable wedges spaced along said member for yieldingly supporting the wall.

10 16. In a device for supporting the wall of a brick kiln, a plurality of supports normally arranged perpendicular to the wall in a supporting relation, and mounting means for said supports permitting displacement 15 thereof from the normal perpendicular position by motion away from the wall.

17. Kiln wall supporting means comprising, in combination, backing means adapted to be fixed alongside and spaced from a 20 kiln wall, and means to be positioned between the wall and said backing means adapted to yield to compression thereon and to yield to a release of compression thereon, whereby said means automatically spans the 25 gap between the backing means and the kiln wall.

18. Brick kiln wall-supporting means comprising, in combination, backing means adapted to be fixed alongside and spaced 30 from a kiln wall, and resilient means adapted to be positioned in the space between the wall and the backing means.

19. Brick kiln wall-supporting means comprising, in combination, backing means adapted to be fixed alongside and spaced 35 from a brick kiln wall, and means adapted to be positioned in the space between said backing means and said kiln wall, said means being arranged to compensate for expansion 40 and contraction of said space.

20. A wall support for brick kilns comprising, in combination, a backing support adapted to be positioned adjacent the wall of a kiln, a plurality of wedges adapted to be 45 held between said support and said kiln wall, each of said wedges spanning the gap between the support and the wall and being free to drop automatically upon a relatively separating movement of the kiln wall 50 and backing support.

21. A brick kiln wall support comprising, in combination, backing means to be positioned adjacent the wall of a brick kiln, means to be interposed between said backing 55 means and said kiln wall, said means being adapted automatically to span the gap between the support and the wall on a separating movement between the said support and said wall.

60 22. An automatically adjustable support for the wall of a brick kiln comprising, a resilient wedge and a backing support for holding said wedge against a wall of a kiln, said support permitting the wedge to drop

on separating movement of the support and 65 kiln wall.

23. A support for the wall of a brick kiln comprising, in combination, a self-adjusting device, a movable backing support for holding said device against a wall of a kiln, and 70 means for attaching said device to the support in order for the device to be carried thereby on moving the support.

24. A hood structure comprising, in combination, a plurality of rigidly connected 75 parallel beams, a plurality of other beams crossing said first mentioned parallel beams, means forming a hood on the under side of the network of beams, dampers in said hood-forming means opening upwardly at the 80 spaces between the beams, and means for simultaneously operating a plurality of said dampers in a group.

25. A hood structure comprising, in combination, a plurality of rigidly connected 85 parallel beams, a plurality of other beams crossing said first mentioned parallel beams, means forming a hood on the under side of the network of beams, and dampers in said hood-forming means opening upwardly at 90 the spaces between the beams.

26. A hood structure comprising, in combination, a plurality of parallel beams, all of said beams on one side of the hood being secured at the ends to a rolling gantry leg, 95 each beam at the other end being secured to a rolling truck, connecting beams between adjacent trucks, a plurality of other beams crossing said first mentioned parallel beams, and means forming a hood on the under side 100 of the network of beams.

27. A hood structure having a framework of steel exposed on the upper side, and a lining on the under side of said framework forming a hood for the collection of heated 105 gases.

28. In combination, an exhaust duct having a plurality of spaced valved ports associated therewith, a hood movable along the line of the exhaust duct and having a 110 plurality of spaced ports adapted to register with a number of the exhaust duct ports, each hood port having an extensible end portion movable toward and away from an exhaust duct port for registry therewith, 115 common means for operating said extensible hood duct ends simultaneously to cause said ports to register, and a yieldable connection between each extensible member and said common operating means. 120

29. In combination, an exhaust duct having a plurality of ports therein, a hood movable along the line of said duct and having a port adapted to register with any port of the exhaust duct, a damper in each exhaust 125 duct port, said damper being arranged to be normally closed and to close automatically, and means associated with said ducts

to hold said damper open when the two ports are in register.

30. In combination, an exhaust duct having a plurality of spaced valved ports associated therewith, a hood movable along the line of the duct and having a port adapted to register with any of the ports of the exhaust duct, said hood port having an extensible end portion movable toward and away from the duct port, and means automatically operable to open the valved duct port when the extensible end moves toward the duct port to register therewith.

31. In combination, an exhaust duct having a plurality of spaced valved ports associated therewith, a hood movable along the line of the duct and having a port adapted to register with any port of the exhaust duct, and means automatically operable to open a valved duct port when the two ports register.

32. A gas collecting hood for brick kilns comprising, in combination, two similar sections adapted to be secured together, each section being a complete and operative hood, sealing means on each edge of each section to close the space between the hood and the walls of the kiln under said section, said means on the adjoining edges of the sections being adapted to be raised from the top of the kiln and to form with each other a seal at the division line of the joined sections, the remaining sealing means of the sections being continuous about the hood formed by the joined sections.

33. In a device of the character described, a gas collecting hood adapted to be moved to cover the open top of a brick kiln, means about the edges of said hood arranged to seal the space between the hood and the top of the kiln walls, said means comprising a plurality of independent flaps movably carried by the hood, each flap being adapted to form a sealing contact at the top of a kiln wall, and means associated with the flaps on one edge for raising the flaps simultaneously away from the kiln wall.

34. In a device of the character described, a gas collecting hood adapted to be moved to cover the open top of a brick kiln, means about the edges of said hood arranged to seal the space between the hood and the top of the kiln walls, said means comprising a plurality of independent members movably carried by the hood, each member being adapted to form a sealing contact at the top of a kiln wall, and operating means for raising a plurality of said members simultaneously to clear the kiln.

35. In a device of the character described, a gas collecting hood adapted to be moved to cover the open top of a brick kiln, and means about the edges of said hood arranged to seal the space between the hood and the

top of the kiln walls, said means comprising a plurality of independent members movably carried by the hood, each member being adapted to find its level on the top of a kiln wall.

36. In a device of the character described having a gas collecting hood for brick kilns, a plurality of flaps hinged to the hood and adapted to rest on the wall of the kiln to seal the space between the kiln and the hood, an operating shaft extending along said flaps, and chains secured to the flaps and arranged to be wound on said shaft.

37. In a device of the character described, a gas collecting hood adapted to be moved to cover the open top of a brick kiln, and means about the edges of said hood arranged to seal the space between the hood and the top of the kiln walls.

38. In a device of the character described, a gas collecting hood for brick kilns, a flap hinged to the hood and adapted to rest on the wall of the kiln to seal the space between the kiln and the hood in the region of the flap.

39. A movably supported gas-collecting hood for brick kilns having adjustable means associated therewith forming a continuous closure or seal for the space between the hood and the walls of a kiln beneath the hood, and suction means arranged to be associated with the hood for drawing gases into the hood from the kiln.

40. A movably supported gas-collecting hood for brick kilns having adjustable means associated therewith forming a continuous closure or seal for the space between the hood and the walls of a kiln beneath the hood.

41. A movably supported gas-collecting hood for brick kilns having a plurality of flexibly arranged independent means associated therewith to form a continuous closure or seal for the space between the hood and the walls of a kiln beneath the hood.

42. In an apparatus for carrying away kiln vapors, the combination of two relatively movable ducts, one of said ducts having a movable section adapted to be advanced into register with the other duct, a valve in said other duct, and means for automatically opening said valve when the movable section is advanced into register with said other duct.

43. In an apparatus for carrying away kiln vapors, the combination of two ducts relatively movable laterally into and out of alinement with each other, a valve in one of said ducts, and means for operating said valve when the ducts are in alinement, said operating means being ineffective when the ducts are out of alinement.

44. The combination of a stationary duct having a branch duct, a valve in said branch

duct, a kiln hood movable along the stationary duct and having a duct adapted to register with said branch duct, and means on the kiln hood for operating said valve.

5 45. The combination of a stationary duct having a branch duct, a valve in said branch duct, a kiln hood movable along the stationary duct and having a duct adapted to register with said branch duct, an arm con-

nected to operate said valve, an arm on said hood arranged to engage the other arm only when the hood duct registers with the branch duct, and means to operate the second arm.

In testimony whereof we have hereunto affixed our signatures.

ALVIN H. COLBERT.

CHARLES R. McCONNELL.
